 Brothers, Watertown, Mass.

Application December 5, 1934, Serial No. 756,044

28 Claims. (Cl. 261—39)

This invention relates to improvements in carburetors and one of the principal objects thereof is to provide improved simple and effective means for controlling the ratio of fuel to air in a combustible mixture supplied to an internal combustion engine while operating under changing or transient conditions, such as occur in an automobile engine while operating in traffic, which tend to disturb or upset the normal functioning of carbureting devices as heretofore constructed.

Such changing or transient loads on an engine produce sudden changes in the speed of the air stream, thus causing surges or eddies which momentarily modify the suction head acting at the fuel outlet, thereby producing fluctuating flow of fuel which momentarily disturbs the ratio of fuel to air mixture supplied to the engine.

It has long been assumed that a sudden increase in the suction head is accompanied by a relative lag in the supply of fuel due to the much greater density of the fuel relative to the air, and numerous fuel accelerating devices have been designed in attempts to overcome this difficulty. It is believed that the converse of this proposition, however, has never been recognized in carburetor design, that is, when the suction head suddenly drops, there is a tendency for the fuel to gush or continue to flow by reason of its greater density as compared with that of the air, thus causing a direct wastage of fuel due to the overenrichment of the mixture at such times. This wastage will be greater as the length of the high velocity stream in the fuel inlet passage is greater.

In certain carburetors as heretofore constructed liquid fuel is delivered to the main air stream through a tortuous passage and application of this analysis to such constructions will immediately reveal the fact that not only uneconomical but even unsteady operation, particularly during light load operations of the engine, must necessarily result.

An object of the present invention is to provide a carburetor with means for coordinating at all times the rate of fuel flow from the fuel supply chamber into the air stream with the quantity of air flowing through the main passage to maintain the ratio of fuel to air irrespective of sudden changes in the air stream velocity, or suction head, in the main passage resulting from the variations in load on the engine, thereby insuring a continuous carrying forward of the fuel from the fuel supply chamber into the air stream of the main passage without diminution or in-

crease relatively to the quantity of air momentarily flowing through the carburetor at any time.

This is attained by a structure in which the fuel passageway is of ample cross sectional area to insure low velocity therethrough, except for a short restricted fuel metering section which discharges fuel directly into air, and effectively avoids lag or gushing flow of any considerable portion of the fuel, such as would be caused by a sharp or abrupt change or reversal in the direction of flow of fuel in any part of the passageway.

More specifically the present invention relates to certain improvements in the type of carburetor disclosed in my prior Patents Nos. 1,823,017, 15 1,823,018, and 1,823,019, granted September 15, 1931, in which a unit control is employed for producing a proper proportioning of the fuel-air mixture in combination with means for effecting uninterrupted mixture flow from the fuel inlet 20 and therebeyond under all normal conditions of operation of the engine from idle to full load.

In specific constructions disclosed therein unit control was obtained by varying the area of the fuel metering section. In the present invention unit control is accomplished by providing means to vary the area of the air metering section.

By the present invention the use of a small valve for controlling the area of the fuel metering section is avoided and inaccuracies in flow resulting from oxidation or gumming of the small valve, which change substantially its flow characteristics, are eliminated; and, inasmuch as the area of the air metering section is many times greater than the area of the fuel metering section, small variations in adjustments of the air metering area are relatively much less disturbing, thereby permitting a far more trustworthy control of fuel to air ratio.

Another object of the invention is to provide the main passage of a carburetor with an air metering valve to provide the normal air metering section thereof having a portion thereof extending in a downstream direction and terminating in front of and in proximity to the fuel outlet, whereby the kinetic energy in the air stream resulting from the high velocity induced in said air metering section is utilized to insure immediate entraining of the fuel in the air stream, without subjecting the fuel outlet to the more intense fluctuations in the suction head which are present when the fuel is discharged directly into the higher velocity air stream in the air metering section.

A further object of the invention is to provide

simple and effective means, preferably including thermostatic means, for accurately adjusting the position of said metering valve to determine positively and with precision the area of the air metering section.

Another object of the invention is to provide a fuel metering section through which all the fuel shall pass during idle, light and medium load operations of the engine, in combination with means for producing continuously a predetermined flowing head at said fuel metering section such as will coordinate the rate of fuel flow with the quantity of air flowing through the air metering section of the carburetor at all times.

A further object of the invention is to provide a fuel metering nozzle having its lengthwise wall converging toward its axis near its outlet end at such an angle as will provide a circular knife edge at the discharge end and insure precision of fuel metering when the nozzle is positioned to discharge fuel upwardly and directly into air.

Another object of the invention is to provide novel means for regulating with precision the level of the fuel in the fuel supply chamber relative to the fuel metering nozzle irrespective of changes in velocity or inclination of the supply chamber.

These and other objects and features of the invention will more fully appear from the following description and the accompanying drawings and will be particularly pointed out in the claims.

Illustrative embodiments of the invention are shown in the accompanying drawings, in which,

Fig. 1 is a vertical central longitudinal sectional view of a carburetor embodying a preferred form of the invention;

Fig. 2 is a plan view of the same with the cover of the float chamber removed;

Fig. 3 is an end elevation of the construction shown in Fig. 1, a portion of the cover and portions of the wall of the main passageway being broken away to illustrate details of construction therein;

Fig. 4 is a side elevation of the construction shown in Fig. 1;

Fig. 5 is a view mainly in vertical section of a down draft carburetor embodying the invention and to which the controlling mechanism illustrated in Figs. 1 to 4 may be applied;

Fig. 6 is a view mainly in vertical section and partly broken away of another embodiment of the invention characterized mainly in that the air metering section of the main air passage is of rectangular form;

Fig. 7 is a vertical section of the view on lines 7—7, Fig. 6;

Fig. 8 is a vertical longitudinal section of the view of a different form of carburetor embodying the invention in which the fuel is introduced into the main passage from below;

Fig. 9 is a top plan view of the fuel supply chamber and the float mechanism therein and also illustrates in dotted lines the relative position of the cylindrical main passage and the mechanism for regulating the throttle valve and the air metering valve;

Fig. 10 is a vertical sectional view of the carburetor shown in Fig. 8 on the broken line 10—10 Fig. 8;

Fig. 11 is a sectional view on lines 11—11 Fig. 8;

Fig. 12 is a view, partly in longitudinal section, of a modification of the construction shown in Figs. 1 to 4, wherein the throttle valve swings in the opposite direction with an elbow leading

from the carburetor downwardly to connect with the downdraft manifold.

Fig. 13 is a side elevation of the general construction shown in Figs. 8 to 10, but in which the air metering valve and the throttle valve swing in opposite directions to those shown in Figs. 8 to 10;

Fig. 14 is an enlarged detail view of the fuel delivery end portion of the tubular member through which liquid fuel is delivered into the air stream; and,

Fig. 15 is a view of the same at right angles to the position shown in Fig. 14.

The carburetor illustrated in Figs. 1 to 4 of the drawings comprises a casing having a tubular portion 1, preferably inclined downwardly, and providing a main air passage 2. The inlet end of the main passage desirably is enlarged and terminates in a cylindrical section 3 adapted to be connected to the usual air cleaner. The opposite end of the tubular section is provided with a peripheral flange 4 provided with suitable bolt holes for connection to a complementary flange 5 of the continued air passage 6 in the form of an elbow which communicates with the inlet manifold of the engine. The casing 7 of a fuel supply chamber desirably is formed integral with and superposed upon the tubular portion 1 of the carburetor casing.

The supply chamber desirably is of a generally rectangular form and is provided with a relatively narrow hollow portion 8 extending lengthwise of the carburetor. The upper wall 9 of the extension 8 is provided with a central aperture having a screw threaded wall which receives the adjustable cylindrical casing 10 which carries the cylindrical valve seat section 11 for an inlet valve. The inlet seat section 11 is enlarged at its upper end to provide a shoulder 12 which engages the upper end of the adjusting valve casing 10. The terminal end of the valve seat section desirably is conical and adapted to receive the flared end of the fuel supply line which is clamped down by the usual cap (not shown).

The adjustable valve casing is provided intermediate of its length with an angular, preferably hexagonal portion 13 to provide means by which the casing may be rotated to adjust it vertically. A lock nut 14 upon the threaded portion of the casing beneath the hexagonal portion is adapted to engage the face of the upper wall 9 and secure the casing in adjusted position.

Desirably further locking means for the adjustable casing is provided comprising an angular plate of the form shown in Figs. 1 and 4 having a vertical portion 15 detachably secured to the side of the extension by screws and a horizontal portion 16 provided with a hexagonal aperture adapted to slip over and closely enclose the hexagonal portion 13 of the casing, thus securely holding said casing in adjusted position. In order therefore to adjust the valve casing, the screws holding the locking plate must be removed and the plate removed from engagement with the hexagonal portion of the casing.

A conical fuel regulating valve 17 engages the lower end of the valve seat member 11 and is provided beneath its conical end with a cylindrical portion of less diameter than the inner diameter of the casing. Suitable ports are provided in the wall of the casing opposite the cylindrical portion to permit free exit of fuel into the supply chamber 18. The lower portion of the valve which constitutes the valve stem 19 desirably is of cylindrical form slidably to fit within

the valve casing and preferably has its walls slabbled off to reduce the friction between the valve stem and the wall of the casing and permit the passage of some of the liquid into the supply chamber. The lower end of the valve stem is 5 spherically rounded and engages a convex surface upon a controlling lever 20 in proximity to the pivot or fulcrum 21 thereof. The controlling lever desirably is of bifurcated or yoke form and the ends 22 and 22^x of the yoke are 10 respectively secured to floats 23 and 24 which are located in the rectangular portion of the supply chamber.

The floats 23 and 24 desirably are of tapering 15 form gradually diminishing in horizontal cross sectional area toward the ends thereof which are remote from the pivot and are symmetrically disposed relatively to a fuel metering nozzle 25 through which fuel is delivered to the air stream 20 in a manner which will hereinafter be more fully described. By reason of this construction, the actuating moment about the pivot 21 of the controlling lever relatively to the regulating valve 25 remains constant for a predetermined level of 25 liquid relative to the fuel nozzle irrespective of changes in inclination of the supply chamber, thereby insuring precise control of the fuel level in the fuel supply chamber.

The fuel nozzle comprises an upwardly inclined 30 cylindrical tubular portion 26 having an enlarged, preferably hexagonal portion 27, and a screw threaded terminal portion 28 which engages complementary screw threads in an aperture in the inclined side wall 29 of a depression chamber 30, a fibre washer 31 being interposed between the enlarged portion 27 and the surfaced face of the wall 29, whereby when the nozzle is screwed in place leakage is prevented, from the supply chamber into the depression chamber.

40 The lengthwise wall of the nozzle gradually and progressively converges toward its axis at its outlet end, where the angle of convergence is more than five and less than twenty degrees to form a restricted fuel metering section through 45 which all of the fuel shall pass during idle, light and normal load operations of the engine. The depression chamber 30 is located centrally of the width of the fuel supply chamber, its width being relatively small compared with its length, and 50 the walls thereof formed integral with the walls 7 of the supply chamber. The wall 29 of the depression chamber extends downwardly and merges into an enlarged preferably rectangular boss 32 which extends downwardly to and 55 merges into the wall of the cylindrical portion of the main air passage.

The rectangular boss 32 is provided with a vertical bore into the upper end of which is inserted the lower end of a deflecting vane 33 having a 60 channel 34 therein, the bottom of said channel presenting a curved surface 35 to deflect the jet of fuel from the nozzle downwardly, during medium and heavier load operations of the engine, into the lower vertical portion of the channel, 65 and thence into a tubular member 36 which extends through the upper wall of and into the main passage. The upper portion of the tubular member is provided with a slightly tapered bore, the upper end of which slightly under- 70 lies the bottom of the channel to avoid any projecting edge which would interfere with the entrance of fuel from the deflecting vane. The tapering bore merges into a cylindrical bore 37 in a lower portion of the tubular member which pref- 75 erably is of sufficiently small cross sectional area

to produce peripheral surface tension of the liquid fuel flowing therethrough which will effectively prevent counterflow of air upwardly into the depression chamber during idle and light load operations of the engine.

The tubular member, which is shown in enlarged detail in Figs. 14 and 15, comprises a cylindrical rod having a conical lower end and is bored axially into but not through its conical lower end. Diametrically opposite sides of the conical lower end portion are cut away thereby providing outlets opening downwardly on opposite sides of a thin flat terminal portion which extends in the general direction of the air current in the main passage. The discharge outlet is below the center of the main passage and is arranged to deliver the fuel downwardly and forwardly beyond the air metering section, so that the air stream in the main passage will carry forward the fuel from the fuel outlet without any tendency to 15 build up back pressure on any portion of the fuel outlet. By reason of this construction the liquid fuel will flow from said outlet in a thin film over said flat terminal portion during idle and light load operations of the engine, and will tend to fall or will be carried directly toward the opening 20 between the lower section of the throttle valve and the complementary wall of the main passage.

The throttle valve 38 is of the "Butterfly" type 25 and desirably is secured to a tapered shaft 39 which is journaled in suitable bosses 40 projecting from the wall of the tubular portion of the casing. The throttle valve preferably presents a flat surface 41 toward the upstream side when in closed 30 position. The upper and lower edge portions are thin and the valve gradually thickens toward the middle to present a stream-line contour when the valve is in open position.

The elliptical contour of the valve is such that when the valve is in closed position the flat surface is at an angle of about seventy-five degrees to the axis of the tubular portion 1 of the main passage. When the throttle valve is in idling position its upper edge is substantially in contact with the complementary upper portion of the tubular wall of the main passage and is in a plane substantially at ninety-degrees or normal with the axis of the main passage. The lower edge of the throttle valve at the same time which is nearest its complementary lower portion of the wall 35 of the main passage is in a plane forming an angle of approximately fifteen-degrees with said normal plane, so that when the valve is rotated toward open position the lower edge of the throttle valve moves away from its complementary 45 wall of the passage much more rapidly than its upper edge moves away from its complementary wall. By reason of this arrangement the lower portion of the throttle valve will concentrate the major portion of the mixture below the throttle 50 valve and along the lower wall of the main passage when in idling and light load positions, thereby effectively carrying forward and entraining the fuel in the air stream. As the throttle valve approaches its wide open position the distribution 55 of fuel-air mixture above and below the valve is much more nearly equal in proportion.

The throttle valve 38 is so mounted that when moved from idle toward open position the lower portion thereof moves toward the terminal section of the fuel outlet, thereby facilitating the entraining and carrying forward of the fuel by the higher velocity of the air stream passing beneath the throttle valve during intermediate load operations.

One of the principal objects of the invention is to provide a trustworthy control for regulating the air to fuel ratio from idle to full load operations of the engine. This is accomplished in the 5 present invention by providing a valve in the main passage to form the normal air metering section thereof and preferably is positioned so that a downstream portion thereof terminates in front of and in proximity to the fuel outlet.

10 In the construction illustrated in Fig. 1 the air metering valve 42 is fixedly secured to a shaft 43 which is journaled in suitable bearings in bosses 44 and 44x extending from the tubular portion 1 of the main casing. The shaft 43 preferably has 15 a reduced slightly tapering section 45 which is hammered or pressed snugly into a complementary hole in the valve. The smaller reduced section may be journaled in the boss 44x or may have an enlarged sleeve 46 secured in place thereon, so that the journaled bearing is of the same size as the other end of the shaft, as illustrated in 20 Figs. 1 and 11. In this method of mounting, valve projections or irregularities of contour on the faces of the valve are avoided and a streamline 25 contour is obtained.

In the particular construction shown in Figs. 1 to 4, the valve 42 is curved in the longitudinal direction of the air passage 2, and is normally positioned at an angle to the longitudinal axis 30 thereof. It has been demonstrated experimentally that if the length of the valve is not substantially greater than its breadth, the turbulence or eddies in the air stream cause an untrustworthy metering of the air in some adjusted positions, and that its length should be more than 35 twenty-five per cent greater than its breadth, so that the valve when in closed position will be at an angle of more than thirty degrees relatively to the longitudinal axis of the main air passage.

40 The valve is so constructed and positioned that the portion extending from its pivot in a downstream direction presents a convexedly curved surface to the higher velocity portion of the air stream and terminates in front of and in proximity to the fuel outlet. The upstream portion is 45 of relatively shorter length and more abruptly curved, thereby causing the major portion of the higher velocity air stream in the air metering section to pass between the downstream portion 50 of the valve and the adjacent wall of the main passage in adjusted positions.

By reason of the position of the lower end of the valve terminating in proximity to the fuel outlet, the kinetic energy persisting in the air 55 stream from the higher velocity created in the major portion of the air metering section will insure immediate entraining of the fuel in the air stream and the carrying forward of the same to beyond the throttle valve during acceleration 60 and normal load or heavy torque operations of the engine without subjecting the fuel outlet to the more intense fluctuations of the suction head which are present when the fuel is discharged directly into the higher velocity air stream in the 65 air metering section.

70 It will be noted from the above description that the liquid fuel is led from the fuel supply chamber into the main air stream through a fuel passageway comprising a nozzle with a restricted fuel metering section therein, into a depression chamber above the main passage from which it 75 flows through a tubular section preferably having small enough cross sectional area to provide peripheral surface tension of the liquid passing therethrough which is effective to prevent coun-

terflow of air upwardly into said depression chamber. The tubular section extends continually downwardly from the depression chamber and terminates in the main passage.

An air duct leading from the depression chamber to the main passage is so positioned as to be subject substantially to the suction head existing at the terminal end of the tubular section. In the construction illustrated in Figs. 1 to 4, an air duct 47 is provided with a branch communicating with the main passage beyond the throttle valve and has coordinated branches communicating with the main passage in front of the throttle valve in such manner as to produce a staged reduction in pressure between the pressure in the depression chamber and the pressure existing beyond the throttle valve during idle and light load operations of the engine.

The duct 47 comprises a vertical bore in the wall of a casing 7 which communicates at its upper end with the depression chamber 30 through a recess 48 in a boss 49 in the cover 50 of the fuel supply chamber. The duct 47 continues downwardly and may communicate through a port 51 with the main passage 2 beyond the air metering section thereof and in front of the throttle valve 38. The duct 47 has a branch 52 communicating with said main passage beyond the throttle valve and having a portion of its length 52x of relatively smaller cross 35 sectional area than that of the port 51. A plug 53 which is inserted across the air duct 47 has a cylindrical bore 54 of approximately the same size as said air duct 47 continuing somewhat more than halfway through said plug, and serves as a means for restricting said air duct to a small cross sectional area intermediate of the depression chamber and the port 51. The plug has an auxiliary port 56 extending axially thereof and communicating with the main passage 2 at a 40 position where the suction head and disturbing eddy currents will be substantially equal to those at the discharge outlet of the tubular member 36.

The auxiliary port 56 is of larger cross sectional area than the smaller cross sectional area of said 45 duct restricting means 55 so that the relative arrangement and different cross sectional areas of said duct and ports above described will produce a staged reduction in pressure between the pressure in said depression chamber and the pressure 50 existing beyond the throttle valve during idle and light load operations of the engine and will maintain continuously a low flowing head in the depression chamber at the metering section of the fuel nozzle.

If desired, the plug 53 may be omitted whereby the duct 47 will extend continuously downwardly to the port 51 and will communicate with the main passage 2 through the port 51 in front of the throttle valve and also will communicate with the main passage through the restricted port 52 beyond the throttle valve. As the area of the port 52 relative to the area of the port 51 is correspondingly smaller the low flowing head will be continuously maintained, during idle and light 65 load operations of the engine, in said depression chamber, but this low flowing head will not be as steady during sudden changes in the position of the throttle valve as when a staged reduction of pressure, as above described, is used.

Inasmuch as there is a substantial flow of air into the port 51 when the low flowing head is being maintained, the port 51 should be so positioned, in the wall of the main passage 2, that fuel from the discharge outlet will not be drawn 75

into it during idle and light load operations of the engine. In the preferred construction where a staged reduction in pressure is produced, this port is preferably placed appreciably above the center of the main passage and appreciably forward of the fuel outlet; and the port 56, through which a relatively much smaller quantity of air enters, preferably is positioned in the side wall of the main passage where the suction head and disturbing eddy currents will be substantially equal to those existing at the fuel discharge outlet.

As an alternative construction, where the air metering valve 42 is moved in coordination with the movement of the throttle valve 38 during idle and light load operations of the engine as hereinafter more fully set forth, the plug 53 may be employed with the duct restricting means 55 omitted, in which case the duct 47 will communicate through the port 56 directly with the main passage 2 and will remain free of fuel during idle and light load operations of the engine and will be subject to substantially the same suction head and disturbing eddy currents existing at the fuel discharge outlet so that momentary or sudden changes in the suction head in the air metering section are not communicated directly to the fuel nozzle.

Inasmuch as air cleaners are almost universally used at the inlet to the main passage of the carburetor, an air vent desirably is employed to equalize the pressure existing in front of the air metering section in the main passage and the pressure existing above the liquid in the supply chamber. In the present construction, the vent comprises a bore 57 extending upwardly and thence abruptly downwardly in a boss projecting from the cover 50 of the fuel supply chamber. The downwardly extending section of the bore 57 communicates with the upper end of a bore 58 which extends downwardly and communicates at its lower end with the main air passage in front of the air metering section thereof.

One of the objects of the invention is to provide regulating means for adjusting the air metering valve 42 to determine positively and with precision the area of the air metering section and preferably includes thermostatic means responsive to changes in temperature of the air entering the carburetor and also may include barometric means responsive to changes in the absolute pressure of the atmosphere in which the carburetor is placed.

In the particular construction illustrated in Figs. 1 to 4, an arm 59 is secured to the end portion of the shaft 43 projecting beyond the cylindrical section of the carburetor casing. The arm 59 preferably is bored to receive the shaft 43 and is slotted and is clamped thereon by a screw 59x. A yoke 60 in the form of a channel is pivotally mounted on the shaft 43 with the inside walls of the channel embracing the edges of the arm 58. A member 61 is suitably secured in the bottom of the channel-shaped yoke 60, as by a rivet 62, and the upper face of the other end of the member 61 engages a suitable abutment. As illustrated in Fig. 4, the abutment comprises a hook-shaped member 63 which is secured to a sylphon bellows 64, the opposite end of which is fixedly secured to a bracket 65 mounted on the casing 1. A screw 66, which is mounted in the arm 58 and engages at its end the under face of the member 61, provides means for adjusting the arm 58 relative to the member 61.

The adjusting screw 66 desirably is provided with a cylindrical notched head 67 and suitable

means are provided for holding the screw in adjusted positions. As illustrated, the holding means comprises a spring member 68 which is secured at one end to the arm 58 by the screw 59x, with the other end suitably positioned to engage the notches in the periphery of the head 67. The end of the screw 66 is maintained continuously in an engagement with the under face of the member 61 by a spring 69, the lower end of which is secured to an eye upon the lever 58 and the upper end of which is secured to a suitable boss 70 projecting from the side wall of the fuel supply chamber.

The member 61 may be a rigid bar, but preferably is a bimetallic thermostatic strip responsive to changes in temperature of the air, and under increases in temperature flexes upwardly at the point of contact between the end of the screw 66 and the underface thereof, thereby causing the valve 42 to increase the area of the air metering section in the main passage, and upon decrease in the temperature of the air to cause the metering valve to restrict the air metering section of the main passage. Adjustment of the screw 66 permits initial position of the air metering valve to determine positively and with precision the area of the air metering section to suit the flow of fuel through the fuel orifice to the particular viscosity of the fuel in use and also to suit the idiosyncrasies of the intake system to which the carburetor is attached.

If the barometric pressure of the atmosphere decreases, the sylphon bellows 64 will expand thereby permitting the abutment 63 to move upwardly and in turn permitting the valve 42 to increase the area of the air metering section. This is distinctly desirable as an altitude control since as the barometric pressure decreases, the volume of the air per pound increases. Thus the increase in the area of the air metering section tends to maintain a better volumetric efficiency of the engine as compared with any structure where barometric means are employed to control the fuel metering area.

Desirably, means are provided to enable the air metering valve to be utilized as a choke valve when starting the engine. In the present construction as shown in Fig. 4 a lever 71 is secured to the arm 58 in any suitable manner as by the screw 59x. The upper end of the lever 71 has attached to it a flexible member, such as a chain 72, which is connected to a control rod 73 extending to the dash of the automobile. The flexible member 72 is normally in a slack condition to permit automatic regulation of the metering valve 42 through the thermostatic or barometric mechanisms above described.

By reason of the construction above described, a carburetor for an internal combustion engine is provided having a main passage, a valve therein restricting its cross sectional area to provide the normal air metering section thereof, remaining constant in area irrespective of changes in load during idle, light and medium load operations of the engine, having means beyond said air metering section to control the flow of air therethrough with means effective by the suction of the engine for delivering fuel to said main passage comprising a fuel supply chamber, a fuel passageway leading therefrom to the main passage, having a restricted fuel metering section through which all the fuel supplied to the main passage shall pass during idle, light and medium load operations of the engine, with an air duct leading from the depression chamber through

the main passage in combination with coordinating air ducts effective during idle and light load operations of the engine to produce continuously a low flowing head at the fuel metering section to supplement the flow induced by the suction in the air metering section together with thermostatic and/or barometric means acting on said air metering valve to change the area of the air metering section of the main passage in response to changes in temperature and/or atmospheric pressure and adjusting means to initially position the air metering valve relatively to the thermostatic and/or barometric controlling means.

15 The invention is illustrated in Fig. 5 as applied to a down draft carburetor. In this construction the tubular portion 74 of the carburetor casing extends downwardly at a suitable angle to the vertical and is provided at its lower end with 20 a flange 74 adapted to be bolted or otherwise secured to a complementary flange upon the inlet manifold of an engine. The casing 76 of the fuel supply chamber is mounted upon or preferably formed integral with the tubular portion 74 of 25 the casing.

The fuel supply chamber may be, and desirably is, the same except as to position of mounting as in the construction disclosed in Figs. 1 to 4. The means for supplying fuel to the main passage 30 of the tubular portion of the casing, the air metering valve, are the same and are designated by the same numerals as in Figs. 1 to 4. The throttle valve 38x is of the "butterfly" type and, as illustrated, is secured to a flattened surface of a shaft 39x which is journaled in bosses projecting from the wall of the casing, as heretofore described. The upper portion of the valve 38x is thickened to delay opening while the lower portion of the valve is bent in an upstream direction whereby 40 the mixture flow is concentrated along the lower wall of the main passage during idle and light load operations of the engine. The mechanisms for regulating with precision the cross sectional area of the air metering section are the same 45 as heretofore disclosed in Figs. 1 to 4 and are not, therefore, illustrated. The operation of the modified construction illustrated in Fig. 5 is the same as that heretofore described.

Another embodiment of the invention is disclosed in Figs. 6 and 7 in which the air metering section of the main passage is of rectangular cross section in which the air metering valve is mounted near the inlet and extends forwardly between parallel walls with its terminal end in 55 proximity to the fuel discharge outlet.

In this construction the tubular portion 77 of the casing is of rectangular form at the air metering section and has vertical walls 78 and 79 and a flat lower wall 80. The air metering valve 81 is of such width as to fit between the walls 78 and 79 with a reasonable tolerance and is connected at its front end to a shaft 82 which is mounted in the upper portions of the walls 78, 79 of the casing in such manner as to seal the 60 passage against the entrance of air over the top of the valve. The lower wall 80 of the tubular section has a downwardly inclined portion extending from the rectangular portion of the passage and merging into a cylindrical inlet section 70 84 adapted to be connected to the usual air cleaner.

The tubular portion of the casing has at its opposite end a cylindrical section 85 which contains a throttle valve 86 secured to a suitable shaft 75 87 extending through the wall thereof. The por-

tion of the casing intermediate of the cylindrical section 85 and the portion between the rectangular air metering section and the cylindrical portion 85 merges from the rectangular section into the cylindrical section thereby providing a downwardly inclined wall 88 extending into proximity to the lower end of the throttle valve. The merging of the side walls of the rectangular air metering section into the cylindrical portion is preferably more rapid in proximity to the air metering section than beyond as illustrated by the shading.

The casing 89 of the fuel supply chamber is superimposed upon and is preferably integral with the tubular portion of the casing and is similar in construction to that heretofore disclosed in Figs. 1 to 4. In this construction, the fuel supply chamber and the means for delivering fuel therefrom to the main air passage are similar to those illustrated in Figs. 1 to 4 and similar parts are designated by the same numerals. The lower end of the deflecting vane 35 communicates with the tubular section 36x which differs from the tubular section 36 shown in Figs. 1 to 4 in that the lower end of the tubular member 36x is cut at an angle to the axis thereof with the upstream portion longer than the downstream portion whereby the fuel is discharged downwardly and forwardly therefrom without any tendency of the air stream to build up back pressure against any part of the fuel discharge outlet. In the construction disclosed in Figs. 6 and 7, all of the air flowing through the main passage is concentrated beneath the air metering valve into an undivided stream in the air metering section and inasmuch as the air metering valve terminates in front of and in proximity to the fuel outlet, the kinetic energy in the air stream resulting from the high velocity induced in said air metering section effects immediate entraining of the fuel in the air stream without subjecting the fuel outlet to the more intense fluctuations in the suction head which are present when the fuel is discharged directly into the air stream in the air metering section.

Another embodiment of the invention is illustrated in Figs. 8, 9, and 10, in which the fuel supply chamber is located below the main air passage instead of above it as in the embodiments of the invention heretofore described. In this construction the carburetor casing consists of a cylindrical portion 90 which desirably is inclined downwardly relative to the horizontal and has an enlarged cylindrical end 91 adapted to be connected to the usual air cleaner with a tapered portion merging therefrom into the cylindrical inlet portion 90. The casing is provided at its other end with a peripheral flange 92 provided with suitable bolt holes for connection to a complementary flange 93 of the continuing air passage in the form of an elbow 94 which communicates with the inlet end of the manifold of the engine.

In this construction the cover 95 of the fuel supply chamber is formed integral with the tubular portion 90 of the carburetor casing. The fuel supply chamber 96 comprises a reservoir of rectangular form having vertical walls 97 and 98 provided with suitable bosses 99 which are secured by screws or otherwise to complementary bosses on the cover 95. The fuel supply chamber is provided at one end with an extension 100, the upper wall 101 of which is provided with an aperture having a screw threaded wall which receives an adjustable valve casing 102 which preferably carries a cylindrical inlet valve seat section 103.

for an inlet valve. The casing 102 has an integral enlarged head 104 preferably of circular form and provided centrally with a smaller upwardly extending rectangular boss 105 adapted to be engaged by a suitable tool for adjusting the valve casing. A fuel inlet fitting surrounds the valve casing and comprises a vertical cylindrical portion 106 which is interposed between the head 104 of the valve casing and a surfaced portion 10 of the upper wall 101 with a horizontal tubular section 107 adapted to be secured to the suitable fuel inlet pipe. The cylindrical section 106 is provided with an enlarged bore 108 extending downwardly from the top nearly to the bottom.

15 The valve casing 102 is provided with the enlarged bore 108 with suitable ports 109 to permit the entrance of fuel from the fitting into the valve casing and thence through the valve seat member.

20 A conical fuel regulating valve 110 engages the lower end of the valve seat member 103 and is provided beneath its conical end with a cylindrical portion of less diameter than the inner diameter of the casing. Suitable ports are provided 25 in the wall of the casing opposite the cylindrical portion to permit free exit of fuel into the supply chamber 96. The lower portion of the valve which constitutes the valve stem 111 is desirably of cylindrical form slidably to fit within the valve casing and preferably has its walls slabbed off to reduce friction between the valve stem of the wall of the casing and to permit the passage of some of the liquid into the supply chamber. The lower end of the valve stem is spherically rounded and engages a convex surface upon a control lever 112 in proximity to the pivot or fulcrum 113 thereof. The control lever 112 desirably is of thin channel-shaped metal and extends beneath and is secured to rectangular floats 114 and 115, 30 which are positioned on opposite sides of the fuel nozzle 116. The nozzle may be and desirably is of the same general construction as that shown in Fig. 1, and comprises an upwardly inclined cylindrical tubular portion having an enlarged, 35 preferably hexagonal, portion 117, and a screw threaded terminal portion 118 which passes through and engages complementary screw threads in the lower wall of the cylindrical casing 96, a fibre washer being interposed between the enlarged portion 117 and a surfaced face on the casing and acting when the nozzle is screwed in place to prevent leakage from the supply chamber into the main passage.

40 The lengthwise wall of the nozzle gradually and progressively converges toward its outlet to form a restricted fuel metering section 119 through which all the fuel shall pass during idle, light and normal load operations of the engine. The floats 114 and 115 are secured to the lever 112 and are located one on either side of the said fuel metering section of the nozzle and at different distances from the pivot 113 of the lever 112. The float 115 which is more remote from the pivot is of smaller horizontal cross section area than is the float 114 and their relative cross sectional areas are such as to cause the actuating moment about the pivot 113 relative to the valve 110 to remain substantially constant for a predetermined level of liquid relatively to said fuel metering section, irrespective of changes in velocity or inclination of the supply chamber in the longitudinal direction of said lever.

45 Preferably the middle portions of the side walls 97 and 98 respectively are made reentrant so that 50 their wall sections 121 and 122 are relatively close

5 to the fuel nozzle for the purpose of reducing the total free surface of the liquid in the supply chamber and also to act as a sort of baffle to prevent excessive agitation of the surface of the liquid in proximity to the fuel nozzle. It is desirable to keep the free surface of the liquid small in the present construction where all fuel passes through the fuel metering section 119 during idle and light load operations of the engine so that when the level of the fuel during heavy load operations of the engine drops, the return to the normal idling level is rapid if the load suddenly be decreased.

10 The normal level of the liquid in the supply chamber may be accurately regulated by placing a suitable shim or shims in the form of thin gaskets 123 between the lower end of the cylindrical wall 106 and the surfaced face of the upper wall 101 of the extension of the fuel supply chamber.

15 The throttle valve which is located in the tubular section of the carburetor casing beyond the fuel nozzle is mounted upon a shaft 125 which is journaled in bosses projecting from the wall of said casing, as heretofore described. The throttle 20 valve desirably is of the same construction as that illustrated in Figs. 1 to 4 having a flat upstream face 126, with thin upper and lower edges and thickened toward the center to form a streamline 25 contour on the lower side of the valve when in open position. Desirably a shallow groove 128 extends from the fuel nozzle along the lower wall of the tubular casing 96 to a point beyond the lower end of the throttle valve when in idling 30 position for the purpose of attenuating any drop or globule of fuel which may tend to form at the lower edge of the fuel nozzle, thereby causing smooth and continuous flow of fuel to beyond the throttle valve during idle and light load operations of the engine.

35 In the construction shown in Figs. 8, 9, and 10, as in that disclosed in Figs. 1 to 4, one of the principal objects of the invention is to provide a trustworthy control for regulating the air to fuel ratio from idle to full load operations of the 40 engine. This is accomplished in a similar manner by providing a valve in the main passage to form the normal air metering section thereof and preferably is positioned so that the downstream portion of the valve terminates in front 45 of and in proximity to the fuel outlet. In this construction an air metering valve 129 is fixedly secured to a shaft 130 which is journaled in suitable bearings in the bosses 131 and 132 extending from the tubular portion 99 of the casing.

50 The connection of the valve 129 to its shaft 130 desirably is similar to that previously described and illustrated in Fig. 11 in respect to the air metering valve 42.

55 In the construction shown in Figs. 8, 9, and 10, the shaft 130 of the air metering valve 129 has secured to it outside of the casing an arm 133 which is bored to receive the shaft and is slotted and clamped thereon by a screw 134. A yoke 135 in the form of a channel is pivotally 60 mounted on the shaft 130 with the inside walls of the channel embracing the edges of the arm 133. A bimetallic thermostatic member 136 is suitably secured in the bottom of the channel shaped yoke 135, as by a rivet 137, and the upper 65 face of the other end of the member 136 engages a suitable abutment to limit the upward movement thereof. A screw 138 which is mounted on the arm 133 provides means for adjusting the arm 133 relatively to the thermostatic member 70 75

136. The adjusting screw desirably is provided with a cylindrical notched head 139, and suitable means may be provided for holding it in adjusting position, as hereinbefore described.

5 A spring 140, the lower end of which is secured to an eye in the lever of the arm 133 and the upper end of which is secured to a suitable anchorage upon the casing (not shown), maintains the adjusting screw continually against 10 the lower face of the thermostatic member and holds the thermostatic member against said abutment.

15 The abutment is preferably in the form of a cam 141 which is secured to the shaft 125 of the throttle valve. The cam preferably is bored to receive the shaft 125 and is slotted and clamped thereon by a screw 142. By reason of this connection, adjustment of the cam relatively to the throttle valve upon the shaft 125 can be readily 20 made.

25 The contour of the face of the cam 143 is such that when the throttle valve is in the middle range of its movement the position of the thermostatic member remains substantially stationary, thereby maintaining the metering valve 129 in normal position throughout a substantial movement of the throttle valve during medium load operations of the engine. The contour of the cam is such as to move said air metering valve 30 from said normal position at a gradual and progressively increasing rate toward a more restrictive air metering position as the throttle valve approaches idling position. Inasmuch as the rate of movement must be relatively much greater 35 as the throttle valve approaches idling position, the main lobe of the cam preferably should extend in a direction to progressively contact with the thermostatic member 136 nearer and nearer to the shaft of the air metering valve, thereby 40 shortening the effective operating length of the thermostatic member as the effective operating length of the cam increases.

45 There is another important feature inherent in this construction in that the effective length of the main lobe of the cam may be varied if its contour is changed accordingly without changing the relative movement of the thermostatic member as the throttle valve approaches idling position. In other words, the operating lengths of 50 the thermostat at and near idling positions can be changed. This permits reasonable leeway in the positioning of the air metering valve in response to changes in temperature during idling and light load operations of the engine. In this 55 construction, a certain amount of sliding action between the face 143 of the cam and the upper surface of the member 136 will tend to abrade the thermostatic member. To prevent the wearing of the thermostatic member, a thin, flexible, 60 wear-resisting strip 144 is positioned between the thermostatic member and the cam, and may be conveniently secured between the thermostatic member 136 and the bottom of the channel 135 by the rivet 137.

65 In some installations it may be desirable to increase the richness of the mixture slightly at wide-open position of the throttle, and in the present construction this is conveniently accomplished by providing the cam 141 with a small lobe 145 which when the throttle valve approaches wide-open position will engage the upper surface of the member 136, thus depressing the same, thereby slightly reducing the area of the air metering section.

70 75 In some installations where operating condi-

tions are fairly steady and sudden accelerations are not imperative, the throttle valve may be mounted to swing in the opposite direction from that shown in the preceding figures, as illustrated in Figs. 12 and 13.

5 The carburetor construction illustrated in Fig. 12 is of the same general construction as that shown in Figs. 1 to 4 comprising a casing 1 having a main passage 2 inclined downwardly which in this case communicates with an elbow 146 10 which extends downwardly and adapted to be connected to a downdraft manifold. As shown in Fig. 12, the downwardly curved elbow extends into the upper portion of an energy-dissipating section of the mixture receiving chamber of a 15 special manifold having a lower distributing section from which the fuel-air mixture is distributed to the several cylinders of the engine, it being found in actual practice that the special manifold of this construction is desirable inasmuch 20 as the precision attained with the present carburetor construction is such that a refinement in manifold design is desirable to obtain the maximum both in efficiency and in smoothness of operation. The elbow 146 is provided at its end 25 with a flange 147 which is secured by suitable screw bolts to the flange 4 of the carburetor casing. In this construction the air metering valve 148 desirably is of streamline construction adapted 30 to concentrate the major portion of the air flow along the lower wall of the main passage 2.

35 The throttle valve 149, which is pivotally mounted upon the shaft 39, is adapted to swing in the opposite direction from that shown in Figs. 1 to 4. This valve is of the same streamline construction as that shown in Fig. 1 and will concentrate the flow of fuel to air mixture beneath its lower portion during idle and light load operations of the engine.

40 In this construction the branch 52 of the air duct 47 leads upwardly instead of downwardly and communicates with the main passage through a restricted portion or port 150 beyond the throttle valve.

45 The construction illustrated in Fig. 13 corresponds to that shown in Figs. 8, 9, and 10, except that the air metering valve and the throttle valve swing in opposite directions.

50 In this construction the casing 98 through which the main air stream passes is inclined downwardly and communicates with a downwardly curved elbow 94. The fuel supply chamber 96 is secured to a cover 95 which is formed integral with the tubular portion 99 of the carburetor casing.

55 In this construction the throttle valve 151 is secured to the shaft 125, and the controlling mechanism therefor is so constructed that the lower portion of the throttle valve in moving toward open position swings in the direction of 60 movement of the air stream.

65 The air metering valve 152 is so mounted upon the shaft 130 that its lower end extends in an upstream direction instead of the downstream direction shown in Fig. 8.

70 The mechanism for controlling the positions of the air metering valve relative to the throttle valve shown in Fig. 13 is similar in all respects to that shown and described with reference to Figs. 8 to 10, except that the cam 141 is secured to the 75 throttle shaft 125 in an upside-down position and must have a slightly different contour 143 in order to compensate the slightly different relation existing between the air metering valve and the throttle valve when swung in opposite di- 75

rections to that shown in Figs. 8 to 10 in order to properly coordinate the rate of fuel flow through the nozzle 116 to the quantity of air flowing through the tubular casing 99.

5 In the construction shown in Fig. 13 the arm 133, the yoke 135, the bimetallic thermostatic member 136, and the adjusting screw 138, and the wear-resisting strip 144, may be the same as the construction shown and described in Figs. 8
10 to 10, except that the positions and movements thereof are in the reverse direction and in that the spring 140 is secured to a lug 153 extending outwardly from the wall of the fuel supply chamber.

15 In the operation of the invention as disclosed in all the adaptations herein illustrated, an air metering valve is provided to restrict a portion of the main passage to provide the normal air metering section thereof where the air is metered relative to the fuel; the fuel is delivered into the main passage near the downstream end of the air metering valve and the throttle valve is located beyond the fuel inlet. The fuel is delivered from the discharge outlet forwardly and the arrangement is such that the air stream between the air metering valve and the throttle valve moves across the fuel outlet without any tendency for the velocity of the air stream to build up a back pressure on any part of the fuel discharge 30 outlet.

35 In all the constructions disclosed herein fuel is delivered from the fuel supply chamber through a restricted fuel metering section in which the fuel is metered relative to the air.

40 The fuel metering section is positioned between float sections in the supply chamber which are connected to a lever to actuate the regulating valve to maintain with precision the level of the fuel in the supply chamber slightly below said fuel metering section during idle and light load operations of the engine.

45 The arrangement is such that all the fuel will pass through said fuel metering section at all times and as the fuel level is slightly below the air metering section means are provided for producing continuously a flowing head at said fuel metering section to coordinate the rate of the fuel flow with that of the quantity of air flow through the air metering section during idle and light load operations of the engine to insure the predetermined fuel-air ratio.

50 In all the constructions means are provided for accurately positioning the air metering valve, preferably including thermostatic means to determine positively and with precision the area of the air metering section.

55 In the constructions disclosed in Figs. 1 to 7 and 12, the float chamber is mounted above the main passage of the carburetor and the fuel is delivered from the fuel supply chamber through an upwardly inclined nozzle having a fuel metering section into a depression chamber from which it flows continually downwardly through a tubular section of sufficiently small cross sectional area to produce peripheral surface tension of the liquid fuel passing therethrough effective to prevent counterflow of air upwardly into said depression chamber during idle and light load operations of the engine.

60 During medium and heavy load operation of the engine the fuel emerges from the nozzle in the form of a jet which impinges against the curved surface of the deflecting vane and is thereby turned downwardly into the tubular section which leads downwardly into the main pas-

sage and delivers the fuel into the air stream in a manner above described.

65 In the constructions disclosed in Figs. 8 to 10 and 13, the fuel supply chamber is located below the main passage of the carburetor and the fuel is delivered therefrom through the fuel metering section of the nozzle directly into the air stream in a manner heretofore set forth.

70 The essentials of the present invention reside quite as much in the cooperative relation between 10 a number of coordinating parts as in the novel construction of particular details. The fuel level must be regulated with a degree of precision not attainable when the float chamber is positioned at one side of the main passage. In all the constructions herein disclosed the fuel supply chamber is centrally located relatively to the main passage, either below or above.

75 This arrangement of the fuel nozzle in the central portion of the fuel supply chamber between float sections on either side is imperative not only for the reason that the float level may change due to variations in inclination of the carburetor; but in operating an automobile under traffic conditions the sudden acceleration or deceleration of the car, as well as swerving or turning the car quickly either to the right or the left, may cause a banking of the fuel which is even more serious than normal changes in the inclination of the carburetor.

80 The total arrangement of parts necessary to deliver liquid fuel into the main air stream, in proper proportions at all times, is such that at no time, even during idle and light load operations of the engine, is a small portion of the air passing through the carburetor required to pick up, accelerate and carry forward the entire fuel supply.

85 These cooperating elements make it possible to provide the regulating means which accurately positions the air metering valve so as to determine with precision the area of the air metering section, thereby providing a unit control to vary the ratio of fuel to air from idle to full load operations of the engine.

90 This unit control permits a single adjustment which from a practical standpoint is capable of being set by an ordinary operator with a degree of precision quite unattainable even by an experienced engineer, without an extended period of tests, where a plurality of coordinated adjustments are required to properly proportion the fuel to air mixture over the whole range of operations of the engine. This unit control also permits the application of a single thermostat to 50 regulate the ratio of fuel to air in a carburetor thereby enormously increasing the practical value of the thermostatic regulation.

95 It will be understood that the particular embodiment of the invention disclosed herein is of an illustrative character and is not restrictive, and that various changes in form, construction and arrangement of parts may be made within the spirit and scope of the following claims.

Having thus described the invention, what is 65 claimed as new, and desired to be secured by Letters Patent, is:

1. A carburetor for an internal combustion engine having a main passage, an air metering valve therein restricting its cross sectional area 70 to provide the normal air metering section thereof, a throttle valve beyond said air metering section to control the flow therethrough, the bottom of said main passage being inclined downwardly from said air metering valve to said 75

throttle valve, means effective by the suction of the engine for delivering liquid fuel to said main passage intermediate of said valves comprising a fuel supply chamber, a fuel passageway leading from said supply chamber to said main passage having a restricted fuel metering section through which all the fuel shall pass during idle, light and medium load operations of the engine, means in said supply chamber to maintain the liquid level therein with precision slightly below said restricted fuel metering section, and means effective during idle and light load operations of the engine for producing continuously a flowing head at said metering section effective to coordinate the rate of flow of fuel with that of the quantity of air flowing through the air metering section.

2. A carburetor for an internal combustion engine having a main passage, an air metering valve therein restricting its cross sectional area to provide the normal air metering section thereof, a throttle valve beyond said air metering section to control the flow therethrough, the bottom of said main passage being inclined downwardly from said air metering valve to said throttle valve, means effective by the suction of the engine for delivering liquid fuel to said main passage intermediate of said valves comprising a fuel supply chamber, a fuel passageway leading from said supply chamber to said main passage having a restricted fuel metering section through which all the fuel shall pass during idle, light and medium load operations of the engine, means in said supply chamber to maintain the liquid level therein with precision slightly below said restricted fuel metering section, means effective during idle and light load operations of the engine for producing continuously a flowing head at said metering section effective to coordinate the rate of flow of fuel with that of the quantity of air flowing through the air metering section, and means for adjusting said air metering valve to determine positively and with precision the area of the air metering section, thereby acting as a unit control to change the ratio of fuel to air from idle through light and heavier load operations of the engine.

3. A carburetor for an internal combustion engine having a main passage, an air metering valve therein restricting its cross sectional area to provide the normal air metering section thereof, a throttle valve beyond said air metering section to control the flow therethrough, the bottom of said main passage being inclined downwardly from said air metering valve to said throttle valve, means effective by the suction of the engine for delivering liquid fuel to said main passage intermediate of said valves comprising a fuel supply chamber, a fuel passageway leading from said supply chamber to said main passage having a restricted fuel metering section through which all the fuel shall pass during idle, light and medium load operations of the engine, means in said supply chamber to maintain the liquid level therein with precision slightly below said restricted fuel metering section, means effective during idle and light load operations of the engine for producing continuously a flowing head at said metering section effective to coordinate the rate of flow of fuel with that of the quantity of air flowing through the air metering section, and thermostatic means acting on said air metering valve to change the area of the air metering section in response to changes in temperature.

4. A carburetor for an internal combustion engine having a main passage, an air metering

valve therein restricting its cross sectional area to provide the normal air metering section thereof, a throttle valve beyond said air metering section to control the flow therethrough, the bottom of said main passage being inclined downwardly from said air metering valve to said throttle valve, means effective by the suction of the engine for delivering liquid fuel to said main passage intermediate of said valves comprising a fuel supply chamber, a fuel passageway leading from said supply chamber to said main passage having a restricted fuel metering section through which all the fuel shall pass during idle, light and medium load operations of the engine, means in said supply chamber to maintain the liquid level therein with precision slightly below said restricted fuel metering section, means effective during idle and light load operations of the engine for producing continuously a flowing head at said metering section effective to coordinate the rate of flow of fuel with that of the quantity of air flowing through the air metering section, thermostatic means acting on said air metering valve to change the area of the air metering section in response to changes in temperature, and adjusting means to initially position said valve relatively to said thermostatic means.

5. A carburetor for an internal combustion engine having a main passage, an air metering valve therein restricting its cross sectional area to provide the normal air metering section thereof, a throttle valve beyond said air metering section to control the flow therethrough, the bottom of said main passage being inclined downwardly from said air metering valve to said throttle valve, means effective by the suction of the engine for delivering liquid fuel to said main passage intermediate of said valves comprising a fuel supply chamber, a fuel passageway leading from said supply chamber to said main passage having a restricted fuel metering section through which all the fuel shall pass during idle, light and medium load operations of the engine, means in said supply chamber to maintain the liquid level therein with precision slightly below said restricted fuel metering section, means effective during idle and light load operations of the engine for producing continuously a flowing head at said metering section effective to coordinate the rate of flow of fuel with that of the quantity of air flowing through the air metering section, and barometric regulating means for adjusting said air metering valve to determine positively and with precision the area of the air metering section in response to changes in pressure of the ambient air.

6. A carburetor for an internal combustion engine having a main passage, an air metering valve therein restricting its cross sectional area to provide the normal air metering section thereof, a throttle valve beyond said air metering section to control the flow therethrough, the bottom of said main passage being inclined downwardly from said air metering valve to said throttle valve, means effective by the suction of the engine for delivering liquid fuel to said main passage intermediate of said valves comprising a fuel supply chamber, a fuel passageway leading from said supply chamber to said main passage having a restricted fuel metering section through which all the fuel shall pass during idle, light and medium load operations of the engine, means in said supply chamber to maintain the liquid level therein with precision slightly below said restricted fuel metering section, and means effec-

5. tive during idle and light load operations of the engine for producing continuously a flowing head at said metering section effective to coordinate the rate of flow of fuel with that of the quantity of air flowing through the air metering section, said throttle valve being constructed and mounted to concentrate the flow of fuel-air mixture beneath it when in idle and light load operating positions.
10. 7. A carburetor for an internal combustion engine having a main passage, an air metering valve therein restricting its cross sectional area to provide the normal air metering section thereof, a throttle valve beyond said air metering section to control the flow therethrough, the bottom of said main passage being inclined downwardly from said air metering valve to said throttle valve, means effective by the suction of the engine for delivering liquid fuel to said main passage intermediate of said valves comprising a fuel supply chamber, a fuel passageway leading from said supply chamber to said main passage having a restricted fuel metering section through which all the fuel shall pass during idle, light and medium load operations of the engine, means in said supply chamber to maintain the liquid level therein with precision slightly below said restricted fuel metering section, and means effective during idle and light load operations of the engine for producing continuously a flowing head at said metering section effective to coordinate the rate of flow of fuel with that of the quantity of air flowing through the air metering section, said throttle valve being constructed and mounted to concentrate the flow of fuel-air mixture beneath it when in idle and light load operating positions, and an elbow forming a continuation of said main passage beyond and adjacent to said throttle valve acting to divert the fuel and air mixture from said main passage toward a vertical direction.
15. 8. A carburetor for an internal combustion engine having a main passage, an air metering valve therein restricting its cross sectional area to provide the normal air metering section thereof, a throttle valve beyond said air metering section to control the flow therethrough, the bottom of said main passage being inclined downwardly from said air metering valve to said throttle valve, means effective by the suction of the engine for delivering liquid fuel into the lower portion of the main passage near the downstream end of the air metering valve and in proximity to the throttle valve, comprising a fuel supply chamber, a fuel passageway leading from said supply chamber to said main passage having a restricted fuel metering section through which all the fuel shall pass during idle, light and medium load operations of the engine, means in said supply chamber to maintain the liquid level therein with precision slightly below said restricted fuel metering section, and means effective during idle and light load operations of the engine for producing continuously a flowing head at said metering section effective to coordinate the rate of flow of fuel with that of the quantity of air flowing through the air metering section.
20. 9. A carburetor for an internal combustion engine having a downwardly inclined main passage through which the air stream shall pass, means for delivering liquid fuel to said air stream comprising a fuel supply chamber, a fuel passageway leading therefrom having a restricted fuel metering section remaining constant in area and through which all the fuel shall pass during idle, light and normal load operations of the engine and having a fuel outlet in said main passage, an air metering valve in said main passage to provide the normal air metering section thereof having a portion extending in a downstream direction and terminating in front of and in proximity to said fuel outlet, and a throttle valve located beyond and in proximity to said fuel outlet, whereby the kinetic energy persisting in the air stream from the high velocity created in the air metering section will insure immediate entraining of the fuel in the air stream and the carrying forward of the same beyond the throttle valve during acceleration and normal load or heavy torque operations of the engine.
25. 10. A carburetor for an internal combustion engine having a downwardly inclined main passage through which the air stream shall pass, means for delivering liquid fuel to said air stream comprising a fuel supply chamber, a fuel passageway leading therefrom having a restricted fuel metering section remaining constant in area and through which all the fuel shall pass during idle, light and normal load operations of the engine and having a fuel outlet in said main passage, an air metering valve in said main passage to provide the normal air metering section thereof having a portion extending in a downstream direction and terminating in front of and in proximity to said fuel outlet, and a throttle valve located beyond and in proximity to said fuel outlet, being constructed and mounted to concentrate the flow of fuel-air mixture beneath it during idle and light load operations of the engine.
30. 11. A carburetor for an internal combustion engine having a downwardly inclined main passage through which the air stream shall pass, a throttle valve in said main passage, means for delivering liquid fuel to said air stream comprising a fuel supply chamber, a fuel passageway leading therefrom having a restricted fuel metering section remaining constant in area and through which all the fuel shall pass during idle, light and normal load operations of the engine and having a fuel outlet in said main passage, an air metering valve in said main passage to provide the normal air metering section thereof having a portion extending in a downstream direction and terminating in front of and in proximity to said fuel outlet, and regulating means for adjusting said air metering valve to determine positively and with precision the area of the air metering section.
35. 12. A carburetor for an internal combustion engine having a downwardly inclined main passage through which the air stream shall pass, a throttle valve in said main passage, means for delivering liquid fuel to said air stream comprising a fuel supply chamber, a fuel passageway leading therefrom having a restricted fuel metering section remaining constant in area and through which all the fuel shall pass during idle, light and normal load operations of the engine and having a fuel outlet in said main passage, an air metering valve in said main passage to provide the normal air metering section thereof having a portion extending in a downstream direction and terminating in front of and in proximity to said fuel outlet, and thermostatic regulating means for adjusting said valve to determine positively and with precision the area of the air metering section in response to changes in temperature.

13. A carburetor for an internal combustion engine having a main passage, an air metering valve therein restricting its cross sectional area to provide the normal air metering section thereof, a throttle valve beyond said air metering section to control the flow therethrough, the bottom of said main passage being inclined downwardly from said air metering valve to said throttle valve, means effective by the suction of the engine for delivering liquid fuel to said main passage intermediate of said valves comprising a fuel supply chamber, a fuel passageway leading from said supply chamber to said main passage having a restricted fuel metering section through which all the fuel shall pass during idle, light and medium load operations of the engine, means in said supply chamber to maintain the liquid level therein with precision slightly below said restricted fuel metering section, and means to maintain said air metering valve in normal position throughout a substantial movement of said throttle valve during the medium load operations of the engine, and to move said air metering valve from said normal position at a gradually and progressively increasing rate toward a more restricted air metering position as the throttle valve approaches idle position, thereby effectively to coordinate the rate of flow of fuel with the quantity of air flowing through the air metering section.

14. A carburetor for an internal combustion engine having a main passage, an air metering valve therein restricting its cross sectional area to provide the normal air metering section thereof, a throttle valve beyond said air metering section to control the flow therethrough, the bottom of said main passage being inclined downwardly from said air metering valve to said throttle valve, means effective by the suction of the engine for delivering liquid fuel to said main passage intermediate of said valves comprising a fuel supply chamber, a fuel passageway leading from said supply chamber to said main passage having a restricted fuel metering section through which all the fuel shall pass during idle, light and medium load operations of the engine, means in said supply chamber to maintain the liquid level therein with precision slightly below said restricted fuel metering section, means for regulating said air metering valve operable in conjunction with the throttle valve to maintain said air metering valve in normal position throughout a substantial movement of said throttle valve during medium load operations of the engine and to move said metering valve from said normal position at a gradually and progressively increasing rate toward a more restricting air metering position as the throttle valve approaches idle position.

15. A carburetor for an internal combustion engine having a main passage through which the air stream shall pass, a throttle valve in said main passage having a shaft extending through the wall thereof, a pivoted air metering valve in said main passage, in front of said throttle valve to provide the normal air metering section thereof, having a shaft rigid therewith extending through the wall of said passage the bottom of said main passage extending downwardly toward said throttle valve, means for delivering fuel to said main passage intermediate of said valve, means for regulating said air metering valve comprising an arm fixedly connected to the shaft of said air metering valve outside of said passage, a thermostatic member pivotally mounted at one

end relatively to the shaft of said air metering valve, a cam secured to the shaft of said throttle valve engaging said member at progressively decreasing distances from said pivot as the throttle is moved toward idle position, yieldable means tending to force said arm into contact with said member and to hold said member against said cam, and shielding means permitting free action of said thermostatic member while protecting the same from the abrading action of said cam.

16. A carburetor for an internal combustion engine having a main passage through which the air stream shall pass, a throttle valve in said main passage having a shaft extending through the wall thereof, a pivoted air metering valve in said main passage, in front of said throttle valve to provide the normal air metering section thereof, having a shaft rigid therewith extending through the wall of said passage the bottom of said main passage extending downwardly toward said throttle valve, means for delivering fuel to said main passage intermediate of said valves, means for regulating said air metering valve comprising an arm fixedly connected to the shaft of said air metering valve outside of said passage, a thermostatic member pivotally mounted at one end relatively to the shaft of said air metering valve, a cam secured to the shaft of said throttle valve engaging said member at progressively decreasing distances from said pivot as the throttle is moved toward idle position, yieldable means tending to force said arm into contact with said member and to hold said member against said cam, and a thin, flexible, wear-resisting strip of material positioned between said thermostatic member and said cam for protecting said thermostatic strip from the abrading action of said cam.

17. A carburetor for an internal combustion engine having a main passage through which the air stream shall pass, a throttle valve in said main passage, a pivoted air metering valve in front of said throttle valve to provide the normal air metering section thereof, having a shaft rigid therewith extending through the wall of said passage, the bottom of said main passage extending downwardly toward said throttle valve, a fuel supply chamber, means for conducting liquid fuel therefrom to said main passage intermediate of said valves comprising a fuel passageway leading from said supply chamber and having a restricted fuel metering section through which all the fuel shall pass during idle, light and normal load operations of the engine, means for regulating said metering valve comprising a member connected to the shaft of said metering valve, a cam operable in conjunction with the movement of the throttle valve having a contour acting upon said member to maintain said metering valve in normal position throughout a substantial movement of said throttle valve during medium load operations of the engine and to move said metering valve from said normal position at a gradually and progressively increasing rate toward a more restricting air metering position as the throttle valve approaches idle position, thereby insuring coordination of the rate of flow of fuel with that of the quantity of air flowing through the air metering section during idle and light load operations of the engine.

18. A carburetor for an internal combustion engine having a main passage through which the air stream shall pass, a throttle valve in said main passage, a pivoted air metering valve in front of said throttle valve to provide the nor-

mal air metering section thereof, having a shaft rigid therewith extending through the wall of said passage the bottom of said main passage extending downwardly toward said throttle valve, a fuel supply chamber, means for conducting liquid fuel therefrom to said main passage intermediate of said valves comprising a fuel passageway leading from said supply chamber and having a restricted section acting as a fuel metering nozzle through which all the fuel shall pass during idle, light and normal load operations of the engine, means for regulating said metering valve comprising a member connected to the shaft of said metering valve, a cam operable in conjunction with the movement of the throttle valve having a contour acting upon said member to maintain said air metering valve in normal position throughout a substantial movement of said throttle valve during medium load operations of the engine and to move said air metering valve from said normal position at a gradually and progressively increasing rate toward a more restricting air metering position as the throttle valve approaches idle position, thereby insuring coordination of the rate of flow of fuel with that of the quantity of air flowing through the air metering section during idle and light load operations of the engine and operable when the throttle valve approaches wide open position to cause said metering valve to slightly decrease said metering section.

19. A carburetor for an internal combustion engine having a main passage through which the air streams shall pass, a throttle valve in said main passage, a pivoted valve in said main passage in front of said throttle valve to form an air metering section thereof having a shaft rigid therewith, the bottom of said main passage extending downwardly toward said throttle valve, means for delivering fuel to said main passage intermediate of said valves, means for regulating said valve comprising a bimetallic member of thermostatic metal pivotally mounted at one end and contacting at the other end with an abutment, and means connected to said shaft contacting with said thermostatic member intermediate of said pivot and said abutment to position said air metering valve in response to changes in temperature, whereby the stiffness of said thermostatic member is increased for a given deflection as compared with a thermostatic member fixedly secured at one end.

20. A carburetor for an internal combustion engine having a main passage, an air metering valve therein restricting the cross sectional area to provide the normal air metering section thereof, a throttle valve beyond the air metering section to control the flow therethrough, a fuel supply chamber, means for conducting liquid fuel therefrom to said main passage comprising a fuel passageway leading from said supply chamber to said main passage having a section provided with a fuel metering nozzle with its axis inclined upwardly, a depression chamber beyond said nozzle and a deflecting vane in said depression chamber having a channel therein the bottom of which presents a curved surface to deflect the jet of fuel from said nozzle downwardly toward the air stream in said main passage beyond the air metering valve during medium and heavier load operations of the engine.

21. A carburetor for an internal combustion engine having a main passage, an air metering valve therein restricting the cross sectional area to provide the normal air metering section there-

of, a throttle valve beyond the air metering section to control the flow therethrough, means for delivering liquid fuel to said passage comprising a fuel supply chamber, a fuel passageway leading from said supply chamber to said main passage having an upwardly extending restricted section acting as a fuel metering nozzle, a depression chamber beyond said nozzle, means to produce persistent fuel flow through said nozzle into said depression chamber during idle and light load operations of the engine, a tubular section of sufficiently small cross sectional area to provide peripheral surface tension upon the liquid fuel passing therethrough effective to prevent counterflow of air upwardly, said tubular section extending downwardly from said depression chamber into said main passage, and a deflecting vane in said depression chamber acting to change the direction of flow of fuel from said nozzle into said tubular section during medium and heavier load operations of the engine.

22. A carburetor for an internal combustion engine having a main passage, an air metering valve therein restricting the cross sectional area to provide the normal air metering section thereof, a throttle valve beyond the air metering section to control the flow therethrough, means for delivering liquid fuel to said main passage comprising a fuel supply chamber, a fuel passageway leading from said supply chamber to said main passage having a fuel metering section remaining constant in area irrespective of changes in load during idle, light and normal load operations of the engine and through which all the fuel shall pass, a depression chamber beyond said fuel metering section, a tubular section extending continually downwardly from said depression chamber into said main passage, and having its discharge outlet below the middle of said main passage and arranged to discharge the fuel downwardly and forwardly and having a continuing structural wall with gradually reduced cross sectional area extending from said outlet downwardly and terminating near the lower wall of said main passage, whereby the fuel will flow from said outlet in a thin film over said structural wall during idle and light load operations of the engine.

23. A carburetor for an internal combustion engine having a main passage, an air metering valve therein restricting the cross sectional area to provide the normal air metering section thereof, a throttle valve beyond the air metering section to control the flow therethrough, means for delivering liquid fuel to said main passage comprising a fuel supply chamber, a fuel passageway leading from said supply chamber to said main passage having a fuel metering section, a depression chamber beyond said fuel metering section, a tubular section of sufficiently small cross sectional area to provide peripheral surface tension upon the liquid fuel passing therethrough effective to prevent counterflow of air upwardly, said tubular section extending continually downwardly from said depression chamber and terminating in said main passage, an air duct leading from the depression chamber to said main passage so positioned as to be free of fuel during idle and light load operations of the engine and to be subject substantially to the suction head existing at the terminal end of said tubular section.

24. A carburetor for an internal combustion engine having a main passage, an air metering valve to restrict a portion thereof to provide the

normal air metering section, a throttle valve beyond the air metering section to control the flow therethrough produced by the suction of the engine, means for delivering liquid fuel to said 5 main passage comprising a fuel supply chamber, a fuel passageway leading from said supply chamber to said main passage having a fuel metering section and a depression chamber beyond said fuel metering section, means effective by the suction head in the air metering section in conjunction 10 with the suction head beyond the throttle to produce persistent fuel flow into said depression chamber during idle and light load operations of the engine, said fuel passageway having a section extending continually downwardly from said depression chamber to said main passage and of small cross sectional area providing peripheral surface tension of liquid fuel passing therethrough effective to prevent counterflow of air 15 upwardly into said depression chamber during idle and light load operations of the engine.

25. A carburetor for an internal combustion engine having a main passage, means to restrict a portion thereof to form an air metering section, a throttle valve beyond the air metering section to control the flow therethrough, means for delivering liquid fuel to said main passage comprising a fuel supply chamber, a fuel passageway leading from said supply chamber to said 20 main passage having an upwardly extending restricted section acting as a fuel metering nozzle, a depression chamber beyond said nozzle, means effective by the suction head in the air metering section in conjunction with the suction head beyond the throttle to produce fuel flow into said depression chamber during idle and light load operations of the engine, said fuel passageway having a tubular section of substantial length 25 extending downwardly from said depression chamber to said main passage and of a small cross sectional area providing peripheral surface tension of the liquid fuel passing therethrough effective to prevent counterflow of air upwardly into said depression chamber during idle and light load operations of the engine, and a deflecting vane in said depression chamber to change the direction of flow of fuel from said nozzle into said tubular section during medium and heavier load operations of the engine.

50. 26. A carburetor for an internal combustion engine having a main passage, means to restrict a portion thereof to form an air metering section, a throttle valve beyond the air metering section to control the flow therethrough, means for delivering liquid fuel to said main passage comprising a fuel supply chamber, a fuel passageway leading from said supply chamber to said main passage having a fuel metering section through which all the fuel shall pass during idle, light and normal 55 load operations of the engine, a depression chamber beyond said fuel metering section, a tubular section extending continually downwardly from said depression chamber to said main passage having a small cross sectional area to provide peripheral surface tension of the liquid fuel passing therethrough effective to prevent counterflow of air upwardly into said depression chamber during idle and light load operations of the engine, and an air duct leading from the depression chamber and communicating with the main passage in front of said throttle valve so positioned as to be free of fuel during idle and light load operations of the engine and acting to stabilize the equaliza-

tion of the pressures in said depression chamber and said main passage.

27. A carburetor for an internal combustion engine having a main passage, means to restrict a portion thereof to form an air metering section, a throttle valve beyond the air metering section to control the flow therethrough, means for delivering liquid fuel to said main passage comprising a fuel supply chamber, a fuel passageway leading from said supply chamber to said main passage having a fuel metering nozzle, a depression chamber beyond said fuel metering nozzle, a section of said fuel passageway extending continually downwardly from said depression chamber to said main passage and having a small cross sectional area to provide peripheral surface tension of the liquid fuel passing therethrough effective to prevent counterflow of air upwardly into said depression chamber during idle and light load operations of the engine, an air duct leading from the upper portion of the depression chamber having a port communicating with said main passage beyond the air metering section and in front of the throttle valve, and a branch communicating with said main passage beyond the throttle valve having a portion of its length of relatively smaller cross sectional area than said port, thereby to maintain continuously a low flowing head in said depression chamber to supplement the suction head induced by the air metering section during idle and light load operations of the engine, and to produce a gradual diminution in said low flowing head as the load is increased beyond idle through light load operations of the engine and without momentary or sudden changes in the suction head acting upon the fuel nozzle.

28. A carburetor for an internal combustion engine having a main passage, means to restrict a portion thereof to form an air metering section, a throttle valve beyond the air metering section to control the flow therethrough, means for delivering liquid fuel to said main passage comprising a fuel supply chamber, a fuel passageway leading from said supply chamber to said main passage having a fuel metering nozzle, a depression chamber beyond said fuel metering nozzle, a section of said fuel passageway extending continually downwardly from said depression chamber to said main passage having a small cross section area to provide peripheral surface tension of the liquid fuel passing therethrough is effective to prevent counterflow of air upwardly into said depression chamber during idle and light load operations of the engine, an air duct leading from the upper portion of the depression chamber and having a port communicating with said main passage beyond the air metering section and in front of the throttle valve, and a branch communicating with said main passage beyond the throttle valve having a portion of its length of relatively smaller cross sectional area than said port, and means restricting said air duct to a small cross sectional area intermediate of said depression chamber and said port, and an auxiliary port leading from said duct intermediate of said depression chamber and said duct-restricting means to said main passage, said auxiliary port being of larger cross sectional area than the smaller cross sectional area of said duct-restricting means and acting to produce a staged reduction in pressure between the pressure in said depression chamber and the pressure existing beyond the throttle valve.
